[57] CLAIM

The ornamental design for a storage carrier for vehicles, as shown and described.

DESCRIPTION

FIG. 1 is a perspective view of the top, front, and side of the storage carrier for vehicles showing my new design;

FIG. 2 is a bottom plan view thereof;

FIG. 3 is a side elevation view thereof, the opposite side being a mirror image of that shown;

FIG. 4 is a front elevational view thereof; and,

FIG. 5 is a rear elevational view thereof.

The storage carrier has been broken away in the middle in FIGS. 2 and 3 for convenience of illustration.
